US00D661166S

(12) **United States Design Patent**
Christopher et al.

(10) **Patent No.:** US D661,166 S
(45) **Date of Patent:** ** Jun. 5, 2012

(54) **WRENCH**

(75) Inventors: **Brent Christopher**, Portland, OR (US);
Da Nian Yang, Shanghai (CN); **Hua An Xu**, Shanghai (CN)

(73) Assignee: **Meridian International Co., Ltd.** (CN)

(**) Term: **14 Years**

(21) Appl. No.: **29/407,421**

(22) Filed: **Nov. 29, 2011**

(51) LOC (9) Cl. **08-05**

(52) U.S. Cl. **D8/25**

(58) **Field of Classification Search** D8/17,
D8/21-29, 97, 107; 81/60, 177.1, 177.85,
81/121.1, 124.3, 165-170, 110.1, 176.2,
81/124.6, 176.1, 176.15, 177.2, 186; 16/110.1;
D15/144.1; 219/75, 227, 229, 121.16, 121.18

See application file for complete search history.
